W. G. NICHOLS.

DIPPER TOOTH.

APPLICATION FILED MAY 24, 1918.

1,275,589.

Patented Aug. 13, 1918.

UNITED STATES PATENT OFFICE.

WESLEY G. NICHOLS, OF CHICAGO HEIGHTS, ILLINOIS, ASSIGNOR TO AMERICAN MANGANESE STEEL COMPANY, OF AUGUSTA, MAINE, A CORPORATION OF MAINE.

DIPPER-TOOTH.

1,275,589.

Specification of Letters Patent. Patented Aug. 13, 1918.

Continuation of application Serial No. 168,074, filed May 12, 1917. This application filed May 24, 1918. Serial No. 236,259.

To all whom it may concern:

Be it known that I, WESLEY G. NICHOLS, a citizen of the United States, and a resident of Chicago Heights, in the county of Cook and State of Illinois, have made and invented certain new and useful Improvements in Dipper-Teeth, of which the following is a specification.

My invention relates to teeth for dippers for excavating and similar machines, and particularly to dipper teeth which are made up of or which comprise a supporting base or shank having a wedge-shaped outer end or nose, together with a detachable and renewable bifurcated point supported by the projecting free end of said base and the diverging arms of which overlie and are interlocked with the inclined faces of the wedge-shaped end thereof, so that when the point becomes worn in use to such an extent as to be no longer serviceable it may be removed, and a new point substituted therefor, thus avoiding the necessity of renewing the supporting base which forms the greater portion of the tooth each time the point portion thereof becomes worn to such an extent as to be no longer capable of effective use, this present case being a continuation of my application for patent for dipper teeth filed May 12, 1917, Ser. No. 168,074.

The object of my invention is to provide a dipper tooth in which the diverging arms of the removable point overlie the inclined faces of the wedge-shaped nose of the shank, as above stated, and in which dove-tailed lugs carried by and extending longitudinally of the inner faces of the diverging arms of the point fit into recesses of corresponding form provided in the inclined faces of the nose of the shank, whereby the said arms are interlocked with the nose and prevented from spreading, and an exceedingly strong connection is provided between the detachable point and the shank or base; the dove-tailed recesses extending longitudinally of the inclined faces of the wedge-shaped nose and the same being substantially arcuate in form, so that their sides may be ground by the side of a circular grinding wheel introduced thereinto whereby recesses are provided in which the lugs will fit tightly, and with a minimum of lost mo-

tion, when the detachable point is in position upon the base or shank.

With the above and other objects in view, my invention consists in the improved dipper tooth and supporting base therefor illustrated in the accompanying drawing and hereinafter described and claimed, and in such variations and modifications thereof as will be obvious to those skilled in the art to which my invention relates.

In the drawing accompanying and forming a part of this specification, and wherein the preferred embodiment of my invention is illustrated:

Fig. 1 is a view showing my improved dipper tooth in plan and as seen from a position within the dipper bucket to which it is attached;

Fig. 2 is a view illustrating a section of my improved dipper tooth taken upon a longitudinally extending plane indicated by the line 2—2 of Fig. 1;

Fig. 3 is a fragmentary view principally in section, the section being taken upon a plane at right angles to the plane of Fig. 2 and indicated by the line 3—3 of said figure;

Fig. 4 is a plan view corresponding with Fig. 1, but showing the end portion only of the shank or base, the detachable point having been removed;

Fig. 5 is a view showing a section taken upon transverse planes indicated by the broken line 5, 5, Fig. 2;

Fig. 6 is a fragmentary sectional view, similar to Fig. 2, but showing my invention as applied to a supporting base having a slot in its extremity to thereby provide for the support of a detachable point having a web connecting its arms, the plane of this view being indicated by the line 6—6, Fig. 7; and

Fig. 7 is a view similar to Fig. 4, but showing my invention as applied to a slotted base of the kind shown in Fig. 6.

Referring to the drawing, the reference numeral 8 designates a supporting base or shank having a recess 9 adapted to fit over the upper or outer end of the lip of the dipper of an excavating machine, the same being secured to the front of the dipper by means of suitable bolts or rivets extending through the holes 10, which base is ordi-

narily designed to remain in permanent position upon the front of the dipper, the point only of the tooth being renewed as the same wears out, as will be appreciated.

The free outer end 11 of the shank 8 is wedge-shaped in form and constitutes a projecting nose upon and to which the detachable point 12 of the tooth is secured, the said detachable point being bifurcated, whereby upper and lower diverging arms 13-14 are provided; which arms overlie and extend along the inclined faces of the wedge-shaped nose, as shown, the lower of said arms 14 preferably extending rearwardly beneath the recess 9 far enough to be engaged by bolts, rivets or other fastening means extending through two of the holes 10, as best shown in Fig. 2, whereby additional security is provided for holding 20 the point in place upon the free outer end of the base.

Located upon and extending along the inner surfaces of the inclined diverging arms 13-14, are inwardly projecting lugs 15, the cross-section of which is dove-tailed in form, as best shown in Fig. 5. These lugs fit into recesses 16 corresponding in cross-section with the cross-section of the lugs, the said recesses being formed one in the 25 upper and one in the lower of the inclined faces of the wedge-shaped nose and extending longitudinally of the same, as best shown in Fig. 2. The side walls of these recesses are in the form of a segment of a 30 circle or disk or, as otherwise expressed, are arcuate in form; this form of side wall being adopted and used in order that the said side walls may be finished and ground smooth by the side of a circular grinding 35 wheel introduced into the recesses, and tipped to an angle corresponding with the angle of the sides thereof and of the lugs 15 which are to fit therein. It therefore follows that a tightly fitting joint is secured between the side walls of the recesses 40 and the side walls of the lugs 15 which contact therewith when the detachable point is in place, thereby reducing lost motion due to looseness of the lugs within the recesses 45 to a minimum and securing contact throughout the entire area of the side walls of the lugs and recesses. It will also be appreciated that the interlocking connection provided by the dove-tailed lugs fitting into 50 the dove-tailed recesses prevents the diverging arms 13-14 of the point from spreading when the tooth is in use, as each arm is interlocked with the inclined face of the nose upon which it rests. Furthermore, 55 when the point of the tooth has been worn to such an extent as to be no longer serviceable for digging the same may be removed by removing the fastenings extending through the two left-hand holes 10, in the 60 embodiment of my invention illustrated,

and moving the point longitudinally, or rather in a direction slightly inclined relative to the longitudinal axis of the base, in the form of my invention shown, and a new and unused point substituted therefor.

70

The interlocking connection provided between each of the diverging arms 14, 15 and the inclined faces of the free end of the supporting base, provides a tooth in which no web extending from one arm of the point to 75 the other is necessary, such as is used in many types of teeth for the purpose of preventing the diverging arms from spreading, as the dove-tail form of the lugs and recesses holds the arms in firm and permanent contact with the inclined faces and prevents the spreading of the arms. My invention, however, is equally applicable to supporting shanks or bases designed to accommodate a detachable point having a web 80 connecting the diverging arms with one another, and such an adaptation of my invention is illustrated in Figs. 6 and 7. In Fig. 6, the forward end or nose of the supporting shank 17 is provided with a slot 18 extending from the free outer end of the nose into the recesses 24 provided in the inclined surfaces thereof, and the detachable point 19 is provided with a web 20 extending between the diverging arms 21, 22 thereof, which 85 web lies within the slot when the point is in place, as shown. The detachable point may be one having a web extending between the diverging arms thereof and in which lugs interlocking with the recesses are not used, 90 as the slot will accommodate the web whether or not the lugs also are present, or both the web and the lugs 23 may be used, as in the form of my invention illustrated; 95 the single supporting base wherein my invention consists being equally well adapted to receive and support detachable points having either the lugs but not the web, the web without the lugs, or both the lugs and the web in a single structure. In this last- 100 mentioned case, *i. e.*, in which both the lugs and the web are present, the lugs will be dove-tailed in cross-section and will fit within the dove-tailed recesses 24, the same as in the form of my invention hereinbefore 105 explained; both the lugs and the web in such cases acting to prevent the spreading of the diverging arms of the point and a much stronger point being thereby secured.

110

Having thus described and explained my 120 invention, what I claim as new and desire to secure by Letters Patent is:—

1. In a dipper tooth, a supporting base having a wedge-shaped nose provided with oppositely disposed faces inclined with reference to one another, and two recesses having inclined side walls whereby a dove-tailed cross-section is secured; said recesses being formed one in each of said inclined faces and extending longitudinally thereof, 125 130

and the same being substantially arcuate in form so that a circular grinding wheel may be introduced thereinto to grind the side walls of said recesses.

- 5 2. In a dipper tooth, a supporting base having a wedge-shaped nose provided with oppositely disposed faces inclined with reference to one another, and two recesses having inclined side walls whereby a dove-
10 tailed cross-section is secured; said recesses being formed one in each of said inclined faces and extending longitudinally thereof, and the same being substantially arcuate in

form so that a circular grinding wheel may be introduced thereinto to grind the side walls of said recesses, said nose having also a slot extending from its free end into said recesses.

Signed at Chicago Heights, in the county of Cook and State of Illinois, this 21st day **20** of May, A. D. 1918.

WESLEY G. NICHOLS.
